DESIGN FOR A TABLE

Application filed November 29, 1930. Serial No. 37,837. Term of patent 7 years.

To all whom it may concern:

Be it known that I, ABE FRIEDMAN, a citizen of the United States, residing in the city and county of Los Angeles, State of California, have invented a new, original, and ornamental Design for Table, of which the following is a specification, reference being had to the accompanying drawings, forming a part thereof.

Fig. 1 is a front view of a table showing my design; and

Fig. 2 is an end view thereof.

I claim:

The ornamental design for a table as shown.

ABE FRIEDMAN.
